UNITED STATES PATENT OFFICE.

SAM SPENCER LORD, OF WHITEFIELD, ENGLAND.

MACHINE FOR TREATING HANKS OF YARN.

Application filed May 19, 1924. Serial No. 714,485.

To all whom it may concern:

Be it known that I, SAM SPENCER LORD, a British subject, residing at 344 Bury New Road, Whitefield, in the county of Lancashire, England, have invented a certain new and useful Improvement in Machines for Treating Hanks of Yarn, of which the following is a specification.

This invention relates to machines for dyeing, washing, scouring, bleaching or impregnating hanks of yarns.

My invention has for its main object to provide a machine whereby the hanks can be partially or completely immersed, and are given a positive continuous revolving motion, a positive continuous rising and falling motion, and a positive and closing motion.

I attain this object by the mechanism illustrated in the accompanying three sheets of drawings, wherein—

Figure 1 is a view in vertical section of a machine in accordance with my invention.

Figure 2 is a plan view, and

Figure 3 is another view in vertical section thereof.

Figure 4 is a view in vertical section of a detail and is drawn to a larger scale than the other figures.

Figure 5 is a view in vertical section and

Figure 6 a plan view illustrating a modification.

Referring to the Figures 1 to 4 of the drawings, in the construction illustrated therein—

I provide a vat 1 having a central wall 2 which produces two main liquid containing portions 3 connected together by narrow liquid containing portions 4 and also a passage 5 through the vat 1. A cage is provided composed of two girders 7 and 9, rigidly connected together at the ends by flanged solid plates 10 and girders 8 are slidably mounted on the cage by means of girders 11 which form with the flanges on the plates 10 slots for the ends of the girders to slide in. For raising and lowering the girders 8 relative to the girders 9 I provide cables 12 connected to the girders 8 and arranged to be wound on drums 13 fixed on a shaft 14 rotatably mounted on one of the girders 7, the cables passing over guide pulleys 15 fixed on shafts 16 which are rotatably mounted on the girders 7. Suitable means (not shown) are provided

for arresting this shaft 14 against rotation in one direction at will. For example a ratchet wheel and pawl may be employed for this purpose. The cage is free to be raised and lowered by any suitable means. I have illustrated by way of example a hydraulic ram 17 for this purpose the ram being arranged to project into the passage through the vat and act on a part 19 fixed by means of bearers 20 to cross pieces 18 secured to the girders 7.

Another suitable means consists of a large worm wheel rotated by means of a driven worm and provided with a crank pin having an antifriction roller which acts on the frame to raise and lower it vertically as the worm wheel is rotated.

The bearers 20 support a cross bearer 21 on which is mounted an electric motor 22 capable of reversal and variation in speed and the motor shaft has a worm 23 mounted on it and meshing with a worm wheel 24 fixed on a shaft 25 mounted on the girders 7. The shaft 25 has two sprocket wheels 26 fixed on its projecting ends. Two depending plates 28 are fixed to the girders 7 and carry adjustable jockey rollers 29.

Elongated studs 30 are rigidly fixed in rows to the girders 8 and 9 and each stud carries a rotatable member of flat shape formation constructed of tubes 31 of flat cross section mounted between guards 32 which are provided on a bush 33 having a gear wheel 34 fixed to it and provided with a screw threaded end 35 to receive a nut 36 which clamps the parts 31 and 32 in position. The gear wheels of each row are in mesh with one another and are driven by a chain 37 from the sprocket wheel 26, the said chain 37 engaging two sprocket wheels 38 fixed to two of the gear wheels 34 on each girder 8 and also engaging a sprocket wheel 39 rotatably mounted on a bracket 40 which is fixed to each girder 9. The sprocket wheel 39 is combined with a gear wheel 41 which meshes with one of the gear wheels 34 of the row of gear wheels on each girder 9.

The gear wheels 34 of the lower row are so set relative to the gear wheels 34 of the upper row that the longer cross sectional axis of each tube 31 of the upper row is displaced 90 degrees relative to the longer cross sectional axis of the corresponding tube 31 of the lower row.

In operation the cage is lifted clear of the vat by means of the hydraulic ram 17

and the shaft 14 is turned so as to lower the girders 8 on the cage. The hanks 42 are then slipped on to the tubes 31, each hank engaging an upper tube and a lower tube. The shaft 16 is then turned so as to wind the cables 12 on to the drums 14, whereby the hanks are straightened or stretched between the tubes 31.

10 The motor is then started and causes the tubes to rotate, whereupon the cage is lowered into the vat which has previously been provided with the liquid necessary for the intended treatment. The hanks are thus moved as they enter the vat. The speed of movement can be varied from an initial high speed to a lower speed or in any other desired manner by variation of the speed of the motor and the movement of the hanks can also be varied by reversal of the motor.

15 It will be appreciated that owing to the flat formation of the tubes 31 and relative angular displacement of the two tubes of each pair carrying a hank, each end of the hank will be alternately opened and closed. Furthermore the hank will be bodily reciprocated in a vertical direction and will also be displaced in the direction of their length, thus setting up an intermittent revolution of the hanks.

20 Thus rotation of the tubes 31 causes the said arms to act on the skeins or hanks in three different ways. In the first place they displace the hanks in the direction of their length and thus set up an intermittent revolution of the hanks. In the second place they lift and lower the hanks bodily for a predetermined distance. In the third place they repeatedly force the sides of skein or hank loop apart and then cause them to approach each other. These three movements ensure a thorough and uniform treatment of all the skeins or hanks and every part of each skein or hank without setting up any undue strain or friction on the skeins or hanks. As both the upper and lower ends of the skeins or hanks are controlled by the tubes 31 against floating in the liquid, they can be moved at a comparatively high speed without detrimental effects, such as the entanglement of adjacent hanks arising. After the critical period in the treatment has passed the motor is controlled to reduce the speed of the shafts which are then run slowly for the remainder of the period of treatment.

25 The quick movement of the skeins or hanks as they are entering the liquid ensures a uniform treatment of all parts of the skeins or hanks.

30 It will be appreciated that in lieu of a flat hank carrying member, such as hereinbefore referred to, two or more arms may be provided mounted on a bracket which may be in the form of a disk. Alternatively oval rollers or their equivalents as hank

carrying members or flat blades or paddles or their equivalents may be provided to rotate about their longitudinal axis.

35 In the construction illustrated in Figure 4 the guards 32 act to prevent the yarn or the like from coming into contact with the driving mechanism or from becoming wedged or caught at the ends of the tubes 31.

40 It will be furthermore appreciated that the cage can be lifted completely out of the vat and be transferred by any suitable means, such as an overhead trolley to another vat for further treatment of the hanks carried by the cage. Furthermore the raising and lowering mechanism may be employed to raise and lower the cage continuously a suitable distance during the treatment in order to impart a fourth movement to the skeins or hanks under treatment.

45 Where arms are employed the arms of each shaft are preferably stayed relative to each or one another at their free ends, the stay means being arranged not to interfere with the placing and removal of the skein or hank.

50 If a smaller machine than that illustrated in Figures 1 to 4 is required, the construction of cage and vat illustrated in Figures 5 and 6 may be utilized. In this construction there is only one movable girder 8 and one fixed girder 9 carried by girders 10 secured at their upper ends by a girder 7 and fixed to end plates 10, cross pieces 18 being provided for the motor and so forth, and guides 11 being provided for the girder 8. The vat is formed with two angular extensions 43 the interiors of which are in open communication with the remainder of the interior of the vat and serve to receive the plates 10. The arrangement is otherwise similar to that illustrated in Figures 1 to 3, the construction shown in Figures 5 and 6 being for single sided machine whilst that illustrated in Figures 1 to 4 is for a double sided machine.

55 The above described means is applicable for all the hereinbefore stated treatments, and makes it possible to employ vat colours in machine dyeing.

60 I claim:—

65 1. A machine for dyeing, washing, scouring, bleaching or impregnating hanks, comprising a raisable and lowerable cage; and pairs of positively and synchronously actuated hank carrying members mounted on the cage to impart a positive continuous revolving motion, a positive bodily rising and falling motion and a positive opening and closing motion to the hanks placed thereon.

70 2. A machine for dyeing, washing, scouring, bleaching or impregnating hanks, comprising a vat for the liquid, a cage adapted to be lowered into and raised out of the vat,

one or more pairs of members rotatably mounted on the cage and geared to rotate at the same speed, and gearing means adapted to drive the said members in all 5 positions of the cage, the said members being of flat formation, the members of each pair being displaced relatively to each other by approximately a right angle and each pair of members being adapted to have a 10 hank placed on them so that they lie within the loop of the hank at the top and bottom of the loop.

3. A machine for dyeing, washing, scouring, bleaching or impregnating hanks, comprising, 15 a raisable and lowerable cage; pairs of hank carrying members; securing means on the cage for securing one of each pair of members rotatably to the frame; and securable adjusting means on the cage for 20 displacing the other of each pair of members towards and away from the first named member of each pair.

4. A machine for dyeing, washing, scouring, bleaching or impregnating hanks, comprising, 25 a liquid vat; a cage mounted to depend into the vat; pairs of hank carrying members rotatably mounted on the cage and each comprising a flat tubular portion; two 30 inwardly disked end portions detachably secured to the ends of the flat tubular por-

tion; driving teeth on one of the end portions; and a cylindrical tubular portion extending through the said portions; and rods on the said cage to engage the cylindrical tubular portions.

5. A machine for treating hanks with liquid, comprising vat means for the liquid, 35 raisable and lowerable cage means; supporting rods fixed to the cage means; an adjustable member mounted on the cage means below the said rods; other supporting rods fixed to the adjustable member in vertical register with the first named rods; flat carrying members rotatably mounted on the said rods to receive the hanks; inter-meshing gear wheels provided on the upper carrying members; inter-meshing gear wheels provided on the lower carrying members; and a chain drive to drive one of the upper carrying members and one of the lower 40 carrying members simultaneously.

In testimony whereof, I have signed my name to this specification at Manchester, in the county of Lancaster, England, this 6th day of May, 1924.

SAM SPENCER LORD.
